United States Patent Office

Des. 222,528
Patented Nov. 2, 1971

222,528
SPINNER NUT

BEST AVAILABLE COPY

Edwin L. Schwartz, Los Angeles, Calif., assignor to
Rite Autotronics Corporation, Los Angeles, Calif.

Filed May 8, 1970, Ser. No. 22,891

Term of patent 14 years

Int. Cl. D08—10

U.S. Cl. D8—273

Fig. 1.

Fig. 2.

Fig. 3

Fig. 4

FIG. 1 is a top plan view of the spinner nut showing my new design;

FIG. 2 is a side elevational view taken from the bottom of FIG. 1;

FIG. 3 is a side elevational view taken from the right side of FIG. 1; and

FIG. 4 is a bottom plan view taken from the bottom of FIG. 1.

I claim:

The ornamental design for a spinner nut, substantially as shown.
